DISPENSING STOPPER FOR A BOTTLE

Ernesto M. Salvatico, 12 Vincent St.,
Newark, N.J. 07105

Filed June 23, 1966, Ser. No. 2,787

Term of patent 14 years

(Cl. D58—10)

FIG. 1 is a front elevational view of a dispensing stopper for a bottle showing my new design;

FIG. 2 is a right side elevational view;

FIG. 3 is a left side elevational view;

FIG. 4 is a rear elevational view; and

FIG. 5 is a right side elevational view in tilted position with the spout in open condition.

The dominant features of my new design reside in the portions shown in full lines.

I claim:

The ornamental design for a dispensing stopper for a bottle, as shown and described.
